UNITED STATES PATENT OFFICE.

ROBERT R. KITCHEL, OF RIDLEY PARK, AND JESSE L. LIPPARD AND JOSEPH E. MULLAN, OF PHILADELPHIA, PENNSYLVANIA, ASSIGNEES TO BAYUK CIGARS INCORPORATED, OF PHILADELPHIA, PENNSYLVANIA, A CORPORATION OF MARYLAND.

CIGAR BUNCH MACHINE.

Application filed February 7, 1925. Serial No. 7,484.

Our invention relates to an improvement in cigar bunch machines of the automatic type, and more particularly to an improved mechanism for effecting the transfer of fillers from the feeding and trimming mechanisms to the rolling mechanism.

The transferring of the fillers from the feed to the rolling mechanism involves considerable difficulty, especially because of the fact that the tobacco forming the filler is in a relatively loose and moistened condition. The principal difficulties arise from the necessity for completely entering the fillers in the transfer and for completely discharging them into the rolling device. The latter difficulty presents perhaps the greatest problem since portions of the tobacco, moist and loose, tend to adhere to the transferring device and resist discharge therefrom, with resultant waste of tobacco and reduction of the quantity of filler in the completed bunches.

In cigar bunch machines heretofore produced, the transfer of the filler has been accomplished, more or less successfully, by means of complicated mechanism, provided with special mechanism, operated in a complicated manner, for ejecting or discharging the filler.

Now it is the object of our invention to provide means for transferring filler of such construction as to readily effect complete reception and discharge of the filler, and adapted to be operated by means of operating mechanism of extreme simplicity in cooperation with associated elements of the bunch machine.

Further objects of our invention are to provide transferring mechanism, which will be simple in construction and operation and efficient and durable in operation.

Having indicated, in a general way, the nature and purpose of our invention, we will now proceed to a detailed description thereof, with reference to the accompanying drawings, in which is illustrated a preferred embodiment, and in which—

Fig. 1 is a view, partly in section, of a

portion of a cigar bunch machine showing an embodiment of our invention.

Fig. 2 is a plan view of a portion of a cigar bunch machine embodying our invention.

Fig. 3 is an end view of a device embodying our invention in open position for the reception of a filler.

Fig. 4 is an end view of the subject of Fig. 3 in closed position.

Fig. 5 is an end view of the subject of Figs. 3 and 4 in discharging position.

a represents the frame of a cigar bunch machine serving to support a pair of guides *b* in which are vertically slidable rods *c*, actuated by means of suitably driven mechanism indicated at *d* through links *e* and by springs *f*. A crosshead *g* is secured to the upper ends of rods *c* and serves to support spaced corrugated cutters *h*, which are adapted, in cooperation with dies *i* in brackets *j*, to trim the ends of the filler, positioned by a reaping device, part of which is indicated by *k*, which, after the filler is trimmed, delivers it to the transferring device and which may be in accordance with the device covered by the application for patent of Kitchel, Mullan and Lippard, Serial No. 7,483, filed February 7, 1925.

Supported by the framework of the machine is a rolling table *l* on which operates a rolling apron or belt *m* of well known construction and operation, in which is adapted to be formed a bight *m'* for the reception of the filler from the transferring device, to which it is delivered by the reaper *k*. Mounted in brackets *n*, secured to the framework of the machine, and extending transversely is a shaft *o*, on which adjacent the brackets are fixedly mounted arms *p*. A pinion *q* is mounted on one end of the shaft *o* and meshes with a quadrant gear *r*, suitably mounted on a pin *s* and adapted to be reciprocated by means of a cam *t*, through the medium of a cam follower arm *u* and an adjustable link *v*.

To the ends of arms *p* are secured rods *w*

which extend laterally toward each other, their ends being spaced apart and to which are secured a filler receiving member or concave jaw α , as shown in Fig. 2. Adjacent the free ends of rods w are secured supporting members or brackets z , slotted longitudinally for the reception of pins 2 extending from the ends of a second filler receiving member or concave jaw y adapted to cooperate with jaw α to form a receiver for a filler. Within the slots in brackets z are springs 3 adjustable by means of screws 4 and adapted to bear on pins 2 and act as resilient supports for jaw y , normally tending to retain jaw y in position to close with jaw α , as shown in Fig. 4. The forward edges of the jaws α and y are notched as at 14.

Cams 7, extending at an angle to the direction of extension of the arm 5 and having heel portions 11, are secured to pins 2 and are adapted to bear on the upper surfaces of extensions 8 on brackets z . Arm 5 and cams 7 act as a lever.

At a convenient point on one of the brackets z there is pivoted, between its ends, a stop 9 one end of which is curved, as at 10, and the other end of which is adapted to be engaged by a hook formed on the lower end of a rod 12 secured to and depending from the crosshead g . A second stop 13 is fixedly secured to the rolling table t adjacent the bight m' in the rolling belt.

The operation of the transferring device will be understood from the following. When the machine is in operation, the cam t effects an oscillation of the quadrant r , which causes pinion q and shaft o to oscillate, with the result that arms p and the jaws α and y carried thereby are swung in an arc from a point adjacent the delivery point of the reaper down into the bight in the rolling belt, as indicated in Fig. 1.

If it be assumed that the transfer is in an intermediate position as indicated in Fig. 1, the jaws α and y will be in closed position, as shown in Fig. 4. If now it be assumed that the transfer is swinging toward the right or forwardly, the operation of the trimming mechanism is so timed that when the transfer approaches its forward position the crosshead g will be in its upper position, with the hook on the lower end of rod 12 engaged beneath stop 9, which is held thereby in fixed position with its curved end 10 in the path of the roller 6 on the transfer. As the transfer completes its forward movement, the roller 6 slides downward, through engagement with the curved end 10 turning the arm and causing the pins 2 to be turned and lifted against the action of their springs 3, through the engagement of the cams 7 on the upper surfaces of extensions 8. As a result of this action, the jaw y is lifted and turned into open posi-

tion for the reception of a filler, as shown in Fig. 3.

The jaw y is maintained in open position by the stop 9 for sufficient time to permit the reaper, which is timed to so act, to deliver into the jaws a filler. The reaper is enabled to partially enter the jaws by virtue of the provision of the notches 14 in the forward edges thereof, in order to completely enter the filler within the jaws, as shown in Fig. 3. The reaper remains momentarily partially entered in the jaws, while the trimming cutters are being actuated. In the downward movement of crosshead g , the rod 12 frees stop 9 which freely swings on its pivot and frees arm 5 which, under the action of springs 3 on pins 2 swings upwardly and permits the jaw y to close with jaw α , as shown in Fig. 5, and encompass the filler, after which the reaper is retracted.

The transfer is then swung to the left or rearwardly and as it approaches its rearward position, in the bight m' of the rolling belt, the roller 6 on arm 5 contacts with the fixed stop 13, which, as the movement of the transfer continues, turns arm 5 resulting in the jaw y being turned and lifted through engagement of the heel portions 11 of cams 7 with extension 8. The travel of the device beyond the point of contact of roller 6 with stop 13 is such that the arm is turned through an arc of about 150° causing the jaw y to positively sweep all of the tobacco comprising the filler out of the jaws from which it will fall into the bight of the rolling belt, as shown in Fig. 5.

Having now fully described our invention, what we claim and desire to protect by Letters Patent is:

1. In a cigar bunch machine, the combination with a filler delivering device and a rolling device, of a filler transfer comprising a fixed jaw and a movable jaw adapted to cooperate to form a receiver, means to move the movable jaw in one direction for the reception of a filler from the delivering device, and means to move said jaw in an opposite direction for discharge of the filler to the rolling device.

2. A filler transfer for cigar bunch machines comprising, in combination, a pair of jaws adapted to cooperate to form a receiver, one of said jaws being pivoted and bodily movable with respect to the other.

3. A filler transfer for cigar bunch machines comprising, in combination, a fixed jaw and a jaw adapted to be rotated and translated, means to translate and rotate said last mentioned jaw to permit the delivering of a filler within said jaws, and means to rotate and translate said jaw whereby the filler will be ejected from said jaws.

4. A filler transfer device for cigar bunch machines comprising, in combination, a pair

- of arms, means to oscillate said arms, a jaw secured to said arms, a second jaw pivotally secured to said arms and adapted to close with said first fixed jaw to form a receiver, 5 means tending to maintain said pivoted jaw in closed relation and adapted to yield to permit said jaw to turn on its pivot and to permit said jaw to be moved bodily relative to said fixed jaw.
- 10 5. A filler transfer device for cigar bunch machines comprising, in combination, a pair of jaws adapted to cooperate to form a receiver, one of said jaws being pivoted and movable bodily in relation to the other, a support for said jaws, means to oscillate said support, means positioned adjacent the limit of oscillation of said support in one direction adapted to rotate and bodily move one of said jaws to permit the insertion of 15 a filler, and means positioned adjacent the limit of oscillation of said support in the opposite direction adapted to bodily move and oppositely rotate said jaw to eject a filler.
- 20 6. A filler transfer device for cigar bunch machines comprising, in combination, a pair of jaws adapted to close to form a receiver, one of said jaws being pivoted and movable bodily relative to the other, means tending to yieldingly maintain said jaws closed, a support for said jaws, means to oscillate said support, a lever carried by said pivoted jaw, a movable stop adjacent the limit of oscillation of said support, means to position said stop to contact with an arm of said lever 25 and cause said pivoted jaw to be rotated and bodily moved thereby to open said jaws for the reception of a filler, means to release said stop to permit said jaws to close, a fixed stop positioned adjacent the limit of oscillation 30 of said support in the opposite direction adapted to contact with an arm of said lever and cause said pivoted jaw to be rotated oppositely and moved bodily to eject the filler.
- 35 7. A filler transfer device for cigar bunch machines comprising, in combination, a pair of arms, means to oscillate said arms, a jaw fixedly supported by said arms, a pair of brackets having slots formed therein secured to said arms, a second jaw adapted to 40 operate with said first mentioned jaw to form a receiver, pins extending from said second jaw through the slots in brackets, an extension on each of said brackets, springs positioned in the slots in said brackets and bearing on said pins, cams on said pins adapted to bear on said extensions, an arm mounted on one of said pins, a stop, means to position said stop in the path of said last 45 mentioned arm adjacent the limit of oscillation of said pair of arms in one direction whereby said jaw will be rotated and said cams actuated to move said jaw bodily against the action of said springs to open said jaws to permit the insertion of a filler, means to release said stop to permit said jaws to close, means to withdraw the delivering device, and a stop positioned adjacent the limit of oscillation of 50 said pair of arms in the opposite position adapted to contact with said last mentioned arm whereby said jaw will be oppositely rotated and said cams actuated to move said jaw bodily to eject the filler.
- 55 8. In a cigar bunch machine, in combination with a filler delivering device, a filler transfer comprising a pair of arms, means to oscillate said arms, a jaw fixedly supported by said arms, a pair of brackets having slots formed therein secured to said arms, a second jaw adapted to 60 operate with said first mentioned jaw to form a receiver, one of said jaws being pivoted and movable bodily relative to the other, means to close and a stop positioned adjacent the limit of oscillation of said pair of arms in the opposite position adapted to contact with said last mentioned arm whereby said jaw will be oppositely rotated and said jaw 70 bodily moved to eject the filler.
- 65 8. In a cigar bunch machine, in combination with a filler delivering device, a filler transfer comprising a pair of arms, means to oscillate said arms, a jaw fixedly supported by said arms, a pair of brackets having slots formed therein secured to said arms, a second jaw adapted to cooperate with said first mentioned jaw to form a receiver, said jaws having notches formed in the adjacent edges, 75 pins extending from said second jaw through the slots in brackets, an extension on each of said brackets, springs positioned in the slots in said brackets and bearing on said pins, cams on said pins adapted to bear on said extensions, an arm mounted on one of said pins, a stop, means to position said stop in the path of said last mentioned arm adjacent the limit of oscillation of said pair of arms in one direction whereby said jaw will be rotated and said cams actuated to move said 80 jaw bodily to eject the filler.
- 90 9. In a cigar bunch machine, the combination with a filler delivering device and a trimming device, of a transfer including a pair of jaws adapted to cooperate to form a receiver, one of said jaws being pivoted and bodily movable relative to the other, means controlled by the trimming device for actuating said pivoted jaw to permit the entry of 95 a filler, means to actuate the delivering device for the delivering of a filler to said jaws, means to close said jaws while said delivering device is in delivering position, and means to actuate said pivoted jaw to 100 eject the filler.
- 100 10. In a cigar bunch machine, the combination with a filler delivering device and a trimming device, of a transfer including a fixed jaw and a movable jaw, means controlled by the trimming device for opening the jaws for the reception of a filler, means to actuate the delivering device to deliver a filler to the jaws, means to close the jaws, and means to actuate the movable jaw to 105 positively eject the filler.
- 110 11. In a cigar bunch machine, in combination with a filler delivering device, of a transfer including a pair of jaws adapted to cooperate to form a receiver, one of said jaws 115

being pivoted and bodily movable relative to the other for reception and ejection of a filler, means for opening said jaws for the reception of a filler, means for entering the delivering device within said jaws, and means for closing said jaws, said jaws being adapted for closure while the delivering device is entered therein.

In testimony of which invention, we have hereunto set our hands, at Philadelphia, ¹⁰ Pennsylvania, on this 21st day of January, 1925.

ROBERT R. KITCHEL.
